UNITED STATES PATENT OFFICE

149,772

DESIGN FOR A COMBINED FISHING ROD AND REEL

William L. Raschke, Fort Worth, Tex., assignor to
The Texas Tackle Company, Inc., Fort Worth,
Tex., a corporation of Texas

Application July 31, 1946, Serial No. 132,159

Term of patent 14 years

(Cl. D31—4)

To all whom it may concern:

Be it known that I, William L. Raschke, a citizen of the United States, residing at Fort Worth, in the county of Tarrant and State of Texas, have invented a new, original, and ornamental Design for Combined Fishing Rod and Reel, of which the following is a specification, reference being had to the accompanying drawing, forming a part thereof.

Figure 1 is a side elevational view of a combined fishing rod and reel, showing my new design.

Figure 2 is a perspective view of the reel and a portion of the rod as shown in Figure 1.
Figure 3 is a rear end elevation thereof.

I claim:

The ornamental design for a combined fishing rod and reel, substantially as shown.

WILLIAM L. RASCHKE.
